(57) **CLAIM**

The ornamental design for a helmet cover, as shown and described.

DESCRIPTION

FIG. 1 is a perspective view of a helmet cover showing my new design.

FIG. 2 is a front view of a helmet cover.

FIG. 3 is a rear view of a helmet cover.

FIG. 4 is a left side view of a helmet cover.

FIG. 5 is a right side view of a helmet cover.

FIG. 6 is a top view of a helmet cover.

FIG. 7 is a bottom view of a helmet cover.

FIG. 8 is a perspective view thereof, showing the helmet cover in the state of use; and,

FIG. 9 is another perspective view thereof, showing the helmet cover in the state of use.

The broken line outline of the partial human figure assists to illustrate the helmet cover in a position of use, but forms no part of the claimed design.
